WILLIAM C. ARMISTEAD, OF FORT WAYNE, INDIANA, ASSIGNOR TO S. F. BOWSER & COMPANY, OF FORT WAYNE, INDIANA, A CORPORATION.

DISPENSING PUMP.

Application filed May 21, 1925. Serial No. 31,774.

The invention relates to dispensing pumps and it is especially directed to means by which the operation of the pump is controlled.

In the dispensing of various liquids it frequently occurs that the quantity of liquid delivered by the pump overflows from the receptacle receiving it and is wasted. This is especially true at filling stations where the customer orders a definite quantity, say five 10 gallons of gasoline for his automobile tank. The pump mechanism is set and operated to deliver five gallons but the tank is filled before the full amount is delivered and overflows onto the ground. Before the discharge 15 valve can be closed and the pump stopped, the liquid continues to flow through the hose and is lost.

The object of my invention is to provide a dispensing pump with means by which it 20 will be automatically stopped when the liquid reaches a selected level in the receptacle and thereby prevent all overflowing of the receptacle.

The invention consists in means for locking 25 the pump mechanism, the means being operated by a movable member that is responsive to an unbalanced pressure upon its opposite sides caused when the liquid reaches a predetermined level in the receptacle.

An adaptation of the invention is illustrated 30 in the accompanying drawings in which

Figure 1 is an elevational view of a simple form of dispensing pump provided with the invention, Fig. 2 an enlarged detail view of the lock operating mechanism, and Fig. 3 a side view of the nozzle and air line.

In the illustrative embodiment of the invention the pump is any form commonly in 40 use for dispensing liquids. A plunger 1^a within the cylinder 1 draws the liquid from a reservoir, usually buried in the ground, and delivers it through a filter 2 and the pipe 3 to the discharge hose 4, a valve 5 controlling the discharge of the liquid through the hose. A rack bar 6 is suitably attached to the 45 plunger rod 1^b and the bar is raised and lowered by a gear or train of gears within the case 7 and having a connection to the hand 50 crank 8.

A latch 9 is pivoted at 10 to a lug or bracket 11 on the case 7 or pump frame 12 and is adapted to swing into engagement with the teeth of the rack and hold the rack and 55 the pump plunger from further movement.

13 represents a diaphragm or other suitable fluid actuating means connected by the rod 14 to the latch 9. A pipe 15 is connected to the opposite end of the member 13 and to a pipe line 16, the upper end of which line 16 60 is connected to a flexible conduit or tube 17 which is suitably attached to the hose 4 and may be disposed inside or on the exterior of the hose. The lower end of the conduit 17 terminates at a predetermined distance 65 above the discharge end of the hose or of the nozzle 18 thereon, so that when the nozzle is inserted into a receptacle, such as the gasoline tank of an automobile, the said lower end of the conduit will determine the 70 approximate height of the liquid the tank should contain and not overflow.

The lower end of the pipe line 16 is connected to a cylinder 19 mounted on the pump frame. A plunger 20 within the cylinder 75 19 is secured to a plunger rod 21 the upper end of which is suitably secured to the rack mechanism 6, so that as the rack bar is reciprocated the plunger 20 will also be reciprocated in the cylinder 19. As the plunger 20 80 rises a vacuum is formed in the cylinder 19 and external air enters the cylinder through the conduit and the pipe line, the discharge of the air being through said line and conduit. As long as air is moving through the conduit and 85 pipe line the member 13 is inoperative and the latch remains in its normal depending position, but when the open end of the conduit is closed, the air pump upon its succeeding up-stroke creates a partial vacuum in 90 the conduit and the pipe line that is almost instantly effective to unbalance the pressure upon the member 13, causing the member 13 to collapse or exert a pull on the latch and cause the latch to swing toward the rack and 95 pass into the space between two of the teeth on the same. The latch and the teeth on the rack are so shaped that when the latch abuts a tooth on the rack the tooth as it moves up or down will draw the latch into the space 100 between that tooth and the next one on the rack and thereby lock the rack against further movement.

When the hose nozzle is inserted into the tank to be supplied and the pump is operated 105 to deliver the quantity of liquid requested the liquid will discharge into the tank in the usual manner. Atmospheric air will be drawn through the conduit and the pipe line by the air pump. Should the level of the 110

liquid reach the lower end of the conduit 17 and close it, a partial vacuum is formed in the pipe line unbalancing the member 13 and causing it to throw in the latch.

- 5 In Fig. 3 I form a seat 22 in the outer end of the tube 17 and provide a ball 23 adapted to engage the seat, a bolt 24 extending through the tube preventing the ball from dropping out of the tube. This ball will normally remain unseated, but should any liquid be drawn into the tube from the container being supplied it will cause the ball to engage the seat and positively close the air line, to set up the vacuum and cause the operation of the latch mechanism. It also prevents the liquid from passing into the air line.

It is evident that any form of latch may be used and that it may be designed or arranged to engage any part of the plunger mechanism of the pump.

What I claim is:

1. In a dispensing pump, a pump mechanism including a plunger and means to actuate the plunger, means to lock the actuating means, a discharge member for the mechanism, a pneumatic member connected to the lock, a conduit leading from one side of the pneumatic member to a selected point adjacent the discharge end of the discharge member for admitting atmospheric air to said side of the pneumatic member, and means operatively connected to the plunger actuating means and having a connection to the conduit for forming a partial vacuum in said conduit and in the pneumatic member when an accumulation of liquid discharged from the discharge member closes the open end of the conduit to unbalance the pressure on the pneumatic member and cause it to move the lock into engagement with the plunger actuating means.

2. In a dispensing pump, a pump cylinder, a plunger within the cylinder, means connected to the plunger for actuating it, a lock adapted to engage the actuating means, a discharge member having communication with the cylinder, a pneumatic member having an operating connection to the lock to cause the lock to engage the actuating means, a conduit having communication with one side of the pneumatic member and terminating at one end at a selected point adjacent to the dis-

charge end of the discharge member for admitting atmospheric air to said pneumatic member, and means operatively connected to the plunger actuating means and having a connection to the conduit to form a partial vacuum in the conduit for unbalancing the pressure on the pneumatic member, said means being responsive to the level of an accumulation of the liquid discharged from the discharge member.

3. The combination with a cylinder and a plunger therein, of a mechanism for actuating the plunger, a lock adapted to be engaged with the mechanism, a discharge member having communication with the cylinder, a pneumatic member connected to the lock for engaging it with the actuating mechanism, a second cylinder having a plunger therein operatively connected to the said actuating mechanism, means having communication with one side of the pneumatic member and with the second cylinder for admitting atmospheric air to the pneumatic member for balancing the atmospheric pressure thereon, the air-intake of said latter means being at a selected point adjacent to the discharge end of the discharge member and being adapted to be closed by an accumulation of liquid discharged from the discharge member whereupon a partial vacuum is formed in the pneumatic member by the second plunger to cause the said member to engage the lock on the actuating mechanism.

4. In a dispensing pump and operating means, including a plunger rack, discharging means, a member to lock the rack, and pneumatic means to operate the locking means and including a pneumatic member operatively connected to the locking means, an air line having its intake adjacent to the discharge orifice of the discharge means, and having communication with the pneumatic member and means to draw air through said air line, the closing of the intake end of the air line by an accumulation of liquid discharged from said orifice unbalancing the pressure on the pneumatic member and causing it to operate the locking means.

In witness whereof I have hereunto set my hand this 9th day of May, 1925.

WILLIAM C. ARMISTEAD.
